TOY OR AMUSEMENT DEVICE

Dan Roth, Yonkers, N. Y.

Application January 20, 1940, Serial No. 314,762

4 Claims. (Cl. 273—102.1)

This invention relates to toys or amusement devices and is herein disclosed in some detail as embodied in a figure adapted to serve as a competitive game.

5 Children, and even grown people, make a sport of throwing a ball to hit an object and enjoy the sport more if the ball rings a bell or knocks an object over, or causes some analogous event. The sport is still more enjoyable if it is humorous and competitive.

10 According to the present invention all these enjoyable features may be embodied in a simple structure, easy to build, cheaply produced in a large way, and rugged enough to withstand the abuse of strong children.

15 In the form shown, a comic head with an open mouth carries a tongue so that, when an object strikes the tongue or presses upon it, the tongue releases a marble or ball with slides down a transparent tube. The tube may simulate a bullet, and may hold any desired number of the balls, and be provided with an open end to deliver the balls for reuse.

20 In the form shown the head is that of a fat man, so that the game is to feed the fat man.

25 Other features and advantages will hereinafter appear.

In the accompanying drawing:

30 Figure 1 is a front view of the device.

Figure 2 is a side view, largely in section. In the form of the invention illustrated, pressure on the tongue 10 in the open mouth 11 of a comical face 12, causes the tongue 10 to swing downwardly or backwardly around a pivot 13 suitably mounted as a cross-shaft in the head 14 behind the face 12.

35 When the tongue 10 thus swings, as when struck by a thrown ball 15, it swings backwardly the long depending arm 16 which is fastened 40 to the tongue so that the arm 16 withdraws a bent-over end 17 from beneath a marble or lighter ball 18 which it has been supporting in a tube 19.

45 As the arm 16 swings backward withdrawing the end 17, an opening 20 in the end swings beneath the ball 18 allowing the ball to drop through a lower tube 21 which at 22 takes the form of a transparent tube 23.

50 At the same time an upward extension 24 of the end 17 pushes a supporting arm 25 under the next higher ball 18 in the tube 19, it extending for this purpose through an opening 26 in the wall of the tube 19. Thus only one ball 18 drops at a time into the transparent front tube 55 23, enabling successive players to keep track of

how many balls 18 they drop into the tube 23 for any given number of throws of the ball 15.

Thus the toy becomes a competitive game. When any desired number of balls 18 are in the tube 23, they may be removed by pushing upward a release arm 27, shown as at the back of the body 28 of the device. The upward pushing of the arm 27 swings it around a pivot 29 carried on ears 30 fastened to a solid back of the tube 23, and swings downwardly and backwardly a closure 31 at the bottom of the tube, so that any desired number of balls 18 may be withdrawn.

In the form shown, each ball 18 as it drops into the tube 23 hits the projecting tongue extension 32 of the pivoted tongue 33 of a bell 34 shown as on the back of the tube 21, thus adding to the attraction of the game.

In the form shown the face 12 has ears 35 and a turned up nose 36 and teeth 37 on the upper jaw and teeth 38 on the lower jaw 39 which is shown as moving with the tongue 10.

In the form shown the lower jaw also includes a fixed member 40, shown as standing for the neck 41 of the face 12, and carrying a flexible flap 42 which may be pushed aside to insert balls 18 within the funnel-like top 43 of the tube 19, the funnel top receptacle accommodating any desired number of balls 18.

In the form shown the funnel 43 includes a tongue 44 bent over the top 45 of a molded section of the neck 46 of the figure, thus supporting the funnel, and, if desired, resembling a necktie.

The front 47 of the figure below the neck 46 35 may be a painted board, with a curved open slot 48 to display the balls 18 in the transparent tube 23, and the tubes 21 and 23 may be held to the back of the board by screws 49 passing through stamped ears 50 attached to the metal or other material of the tubes. The tube 19 may be likewise held by a screw 51 in ears 52.

The figure may stand on simulated shoes 53 and be supported by a metal bracket 54 hinged to one of the ears 50 and kept from sliding by a rubber sleeve 55 adapted to rest upon the floor, and by an upward arm 56 adapted to lie against the back of the tube 23, for example.

The metal bell crank 16 may be integral with the metal arm 57 to which the tongue 10 is suitably held, and the balance of the backwardly inclined bell crank 16 is such that after releasing a ball 18 its end 17 swings back to hold the next ball 18 as it drops down.

Having thus described one embodiment of the invention, what is claimed is:

1. A figure having a mouth resembling an animal and including a movable tongue, a receptacle below the tongue for holding balls, a pivot on which the tongue swings as it moves, an arm attached to the tongue and normally holding a ball, and adapted to be swung by depressing the tongue to release the ball, and a tube 10 behind the mouth and having a transparent face in the position of a gullet through which the released ball falls.

2. A figure having a mouth resembling an animal and including a movable tongue, a receptacle below the tongue for holding balls, a pivot on which the tongue swings as it moves, an arm attached to the tongue and normally holding a ball and adapted to be swung by depressing the tongue to release the ball, and a tube 15 behind the mouth and having a transparent face in the position of a gullet through which the released ball falls, and a bell rung by the falling ball.

3. A figure having a mouth resembling an

animal and including a movable tongue, a receptacle below the tongue for holding balls, a pivot on which the tongue swings as it moves, an arm attached to the tongue and normally holding a ball and adapted to be swung by depressing the tongue to release the ball, and a tube 5 behind the mouth and having a transparent face in the position of a gullet through which the released ball falls, and a releasable device for holding balls in the tube.

4. A figure having a mouth resembling an animal and including a movable tongue, a receptacle below the tongue for holding balls, a pivot on which the tongue swings as it moves, an arm attached to the tongue and normally holding a ball and adapted to be swung by depressing the tongue to release the ball, and a tube behind the mouth and having a transparent face in the position of a gullet through which the released ball falls, and a bell rung by the falling 20 ball, and a releasable device for holding balls in the tube.

DAN ROTH.
